(57) **CLAIM**

The ornamental design for a tire as shown and described.

DESCRIPTION

FIG. 1 is a front view of a tire showing my new design; FIG. 2 is a partial, enlarged view of FIG. 1; FIG. 3 is a rear view thereof; and, FIG. 4 is a partial, enlarged view of FIG. 3.

The drawings include shadows and reflections which indicate contour, not surface ornamentation.

The broken lines depict boundaries which form no part of the claimed design. In FIGS. 1 and 3, the blurred portions in the drawing form no part of the claimed design.
